UNITED STATES PATENT OFFICE.

CHARLES L. DEPOLIER, OF NEW YORK, N. Y.

WATCHCASE, &c.

1,139,109.

Specification of Letters Patent. Patented May 11, 1915.

Application filed February 1, 1915. Serial No. 5,415.

To all whom it may concern:

Be it known that I, CHARLES L. DEPOLIER, a citizen of the United States, residing in the borough of Brooklyn of the city of 5 New York, in the county of Kings, in the State of New York, have invented certain new and useful Improvements in Watch-cases, &c., of which the following is a specification, reference being had to the accompanying drawing, forming a part hereof.

This invention relates particularly to what are commonly known as convertible watches, that is, watches which can be used either as wrist watches or as chatelaine or 15 sautoir watches. Such watches, in order to be used as wrist watches, must be provided at opposite points with two means of attachment to the bracelet. The bow of the watch usually serves as one of such 20 means of attachment and at the opposite point the watch-case is usually provided with a permanently projecting eye or loop of some sort to which one end of the bracelet may be secured. It has been proposed here- 25 tofore to provide, as such second means of attachment, something which shall not be readily visible when the watch is in use as a chatelaine or sautoir watch, in order that it may not appear that the wearer is then 30 using a convertible watch, that is, a watch which, from motives of economy, is designed to be used also for a different purpose.

It is the object of this invention to provide an improved form of connecting means 35 to which the bracelet may be connected and itself shall not be readily seen, disappearing into the watch-case center flush with the periphery when the watch is used as a chatelaine or sautoir watch.

40 In accordance with the invention the watch-case center is provided at a point opposite the bow, or at each of two points, if desired, with a hole or recess adapted to receive a loop which may be concealed within 45 the hole or recess or drawn out so as to be engaged by a snap ring or hook, but without being wholly disengaged from the watch-case center. In order that the loop may be as small as practicable, the watch-case center 50 may also be recessed or dished slightly on its outer surface so as to permit the hook or snap ring to lie partly within such dished recess.

The invention will be more fully ex-

plained hereinafter with reference to the 55 accompanying drawing in which it is illustrated and in which—

Figure 1 is a view in perspective of a bracelet and a watch equipped with the improved device. Fig. 2 is a view on a larger 60 scale, partly in elevation and partly in section, of a watch-case which embodies the invention, the terminal link of a bracelet being also shown in operative engagement therewith. Fig. 3 is an edge view of the 65 watch-case shown in Fig. 2, partly in section on the plane indicated by the line 3—3 of Fig. 2, the terminal link of the bracelet being also shown. Fig. 4 is a detail view 70 in section corresponding to Fig. 2 but with the movable loop pushed in. Fig. 5 is an edge view of the watch-case as seen from the right hand in Figs. 2 and 4. Fig. 6 is a view similar to Fig. 3 but showing the 75 terminal link of the bracelet as connected with the watch-case through the intermediary of a swiveled snap ring.

In Fig. 1 of the drawing is shown a wrist or bracelet watch *a* having an ordinary bow *b* to which is attached one end of a bracelet 80 *c*, the other end being attached to the watch at a point, as *d*, diametrically opposite the bow *b*, as hereinafter described.

In the embodiment of the invention illustrated in the several figures of the drawing, 85 the center *e* of the watch-case, having on one side the back *e'* and on the other side the bezel *e''*, has formed therein at a convenient point, preferably opposite the bow *b*, or at each of two diametrically opposite points, a 90 recess *e³*, with its ends normal but slightly undercut so as to leave shoulders *e⁴*. The watch-case center is also formed exteriorly and on opposite sides of the mouth of the recess *e³* with a concaved or dished recess, as 95 at *e⁵*. Seated in the recess *e³* is a movable loop *f* which may be pushed in so as to be received wholly within the recess, as shown in Fig. 4, and thereby to become practically invisible, or may be drawn out, as shown in 100 Figs. 1, 2, 3 and 6, so that it may be engaged by a hook member *c'* of a bracelet *c* as shown in Fig. 3 or by a swiveled snap ring *c''*, as shown in Fig. 6. The outward movement of the loop *f* is limited, so as to prevent disengagement of the loop from the watch-case, 105 by any suitable means, as by having its legs *f'* slightly bent over to form lugs or stops *f''*.

to engage the shoulders e^4 previously referred to. The concave recessing of the exterior face of the watch-case center e , as at e^5 , permits the hook or snap ring to be engaged with the loop, when it is drawn out, without requiring the loop to be so long, in a radial direction with respect to the watch-case, as would otherwise be required.

It will be understood, of course, that the 10 deep recess or hole and the loop itself may be variously formed so as to permit the loop to be pushed entirely into the hole, so as to be concealed therein, and to prevent the complete disengagement of the loop from the 15 watch-case when the loop is drawn out and that the invention, therefore, is not limited to the precise details of construction shown and described herein.

I claim as my invention:—

20 1. A watch-case having its center formed with a deep recess or hole, a loop adapted to be received and concealed within said deep recess or hole and to be drawn out for engagement with a hook or snap ring, and
25 means to prevent complete disengagement of

the loop from the watch-case when drawn out.

2. A watch-case having its center formed with a deep recess or hole on its exterior surface, and also formed adjacent to the 30 deep recess or hole with a concaved or dished recess, and having a loop adapted to be received and concealed within the deep recess or hole and to be drawn out for engagement with a hook or snap ring.

3. A watch-case having its center formed with an undercut deep recess or hole and a loop adapted to be received and concealed within said deep recess or hole and to be drawn out for engagement with a hook or 40 snap ring and having its legs formed with lugs to engage the shoulders of said deep recess or hole to prevent complete disengagement of the loop from the watch-case.

This specification signed and witnessed 45 this 29th day of January, A. D. 1915.

CHARLES L. DEPOLIER.

Signed in the presence of—

FRANCIS J. MURPHY,
WORTHINGTON CAMPBELL.
